UNITED STATES PATENT OFFICE.

LEE ROBERT MILLER, OF NEW YORK, N. Y.

ATTACHMENT FOR HOISTING SLINGS.

Application filed May 27, 1927. Serial No. 194,773.

This invention relates to an attachment for hoisting slings.

An object of the invention is to provide an attachment which is secured to the loop 5 of a cable or analogous sling and which functions to insure the centering of the lift or pull relative to the beam or other part being lifted, and to cause said beam or part to be lifted at the desired angle.

10 A further object is to provide an attachment of this character which by reversal is adapted for use without removal on different sizes of beam and which not only functions to insure a proper centering of the beam and 15 sling relative to each other but also spreads the loop to prevent an undue bite in the loop.

A further object of the invention is to provide an attachment of this character which can be manufactured and sold at a 20 reasonably low price, which will enable the beam to be lifted without danger of slippage of the sling, and which will most efficiently perform the functions for which it is intended.

25 With these and other objects in view, the invention consists in certain novel features of construction and combinations and arrangements of parts which will be more fully hereinafter described and pointed out in the 30 claims.

In the accompanying drawings—

Figure 1 is a view showing the sling in elevation and an I-beam in section, with my improved attachment in operative position 35 on the sling;

Figure 2 is a view similar to Figure 1, showing the attachment reversed for a larger size of beam;

Figure 3 is a view in side elevation looking at the right hand side of Figure 2;

Figure 4 is a view in section on the line 4—4 of Figure 5;

Figure 5 is a view in side elevation of the attachment in operative position on the loop 45 of a sling;

Figure 6 is a plan view of Figure 5;

Figure 7 is a view on a reduced scale showing how the sling may be positioned longitudinally around the beam with my improved attachment thereon.

50 1 represents a cable which may be of steel or any other suitable material and which has a loop 2 at one end through which the cable is positioned after being located around a 55 beam 3 or other part to be lifted. I have shown the beam 3 as an I-beam but it is ob-

vious that any other form of beam or analogous article may be lifted.

My improved attachment comprises two angle bars 4 and 5, the former being preferably wider or higher than the latter so that the laterally projecting flange 6 of bar 4 is normally in a higher plane than the laterally projecting flange 7 of bar 5. The bar 5 is preferably formed with recesses or seats 8 to 65 receive the two runs of the loop 2.

U-bolts 9 are projected through registering openings in the bars 4 and 5 and have nuts 10 screwed thereon so that when said nuts 10 are screwed home with the attachment properly positioned on the runs of the loop 2 the attachment will be rigidly secured to the loop and will hold the loop spread so that the cable will not bite unduly into the sling. In other words, without such a 70 spreader the sling is drawn with its sides more or less parallel and a very sharp angular bite is had in the sling which oftentimes results in injury to the sling. This, however, is only one part of my invention, the 75 primary object of the same being to engage the beam 3 so that the cable will properly center on the beam, as clearly illustrated in Figures 1 and 2.

In operation, after the attachment is 80 clamped on the loop of the sling and the sling located around the beam 3, one of the bars 4 and 5 will engage under a flange of the beam, as clearly indicated in Figures 1 and 2. This reversal of the parts is desirable 85 as it enables either the bar 4 or the bar 5 to engage under the flange of the beam, as shown in Figures 1 and 2, respectively, so as to center the cable or sling with relation to the beam and use the attachment without adjustment on different sizes of beam.

It is of course to be clearly understood that the attachment may be adjusted on the loop so as to properly center the pull of the cable on any size of beam, but in any event 90 by simply reversing the loop, different sizes of beams may be properly accommodated in the sling.

Furthermore, I preferably provide a central recess 11 in the bar or rather in the 105 flange 7 of said bar so that in the event it be desired to have several runs of cable or rope around the bar they may be accommodated in this recess and centrally disposed relative to the attachment.

110 As shown in Figure 7, the attachment may be used to engage one end of the beam 3

with the sling positioned longitudinally around the beam so as to allow the beam to be lifted at any desired angle.

While I have illustrated what I believe to be a preferred construction, it is to be distinctly understood that I do not wish to be limited to such construction but desire to cover the idea broadly of an attachment which which not only spreads the loop of a hoist but engages the beam or other part to be lifted so as to properly center the pull of the hoist relative to the beam or other article. Hence various changes and alterations might be made in the general form of the parts described without departing from my invention and therefore I do not limit myself to the precise details set forth but consider myself at liberty to make such changes and alterations as fairly fall within the spirit and scope of the appended claims.

I claim:

1. An attachment for hoisting slings, including a pair of members adapted to be clamped to the runs of the loop of the sling intermediate the ends of the sling and engage a beam or other article to be hoisted.
2. An attachment for hoisting slings, including a pair of members adapted to be clamped to the runs of the loop of the sling

and engage a beam or other article to be hoisted, both of said members comprising angle bars, one of which is appreciably wider or higher so that it is normally disposed in a plane higher than the other whereby when the sling is reversed the attachment is adapted for another size or sizes of beam.

3. An attachment of the character described, comprising a pair of angle bars adapted to engage the runs of a sling between them, the flange of one bar being in a higher plane than the flange of the other.

4. An attachment of the character described, comprising a pair of angle bars adapted to engage the runs of a sling between them, the flange of one bar being in a higher plane than the flange of the other, and one of said flanges having a central recess therein.

5. An attachment of the character described, comprising a pair of angle bars adapted to receive the runs of the loop of a sling between them, one of said bars having recesses accommodating the runs of the loop, U-bolts projected through the bars, and nuts on the said bolts.

LEE ROBERT MILLER.
